UNITED STATES PATENT OFFICE.

MURRAY WITT, OF BROOKLYN, NEW YORK.

DESIGN FOR AN ORNAMENT FOR AUTOMOBILE RADIATORS OR THE LIKE.

Application filed October 18, 1927. Serial No. 23,786. Term of patent 7 years.

To all whom it may concern:

Be it known that I, MURRAY WITT, a citizen of the United States, residing at 1729 Ocean Parkway, Brooklyn, in the county of Kings and State of New York, have invented a new, original, and ornamental Design for an Ornament for Automobile Radiators or the like, as shown in the accompanying drawing and described in the following specification.

Fig. 1 is a front elevational view of an ornament for automobile radiators or the like showing my new design; and Fig. 2 is a side elevational view thereof.

I claim:

The ornamental design for an ornament for automobile radiators or the like as shown.

MURRAY WITT.
